UNITED STATES PATENT OFFICE.

VICTOR H. EMERSON, OF NEW YORK, N. Y., ASSIGNOR TO AMERICAN GRAPHOPHONE COMPANY, OF BRIDGEPORT, CONNECTICUT, A CORPORATION OF WEST VIRGINIA.

REPRODUCER FOR GRAPHOPHONES.

1,026,084.

Specification of Letters Patent.

Patented May 14, 1912.

Application filed April 15, 1905. Serial No. 255,802.

To all whom it may concern:

Be it known that I, VICTOR H. EMERSON, a citizen of the United States, and a resident of New York city, New York, have 5 invented a new and useful Reproducer for Graphophones, which reproducer is fully set forth in the following specification.

This invention relates to talking-machines employing disk records which have vertically undulating record-grooves.

In machines employing ordinary disk records, the record-groove is relied upon to feed the sound-box across the disk, the spiral groove acting as a feed-screw. Here- 15 tofore, vertically undulating sound-grooves have generally been confined to cylindrical tablets; and when applied to disk tablets they fail to feed the sound-box properly, because of their shallowness,—the stylus 20 being liable to leave the track, skipping one or more grooves and giving imperfect reproductions.

One object of the present invention is to provide a talking-machine in which vertically undulating disk records may be employed that will properly feed the sound-box. Again, disk records have heretofore required a fresh stylus (or "needle") for each reproduction, whereas cylinder records 30 (with their vertically undulating grooves) employ the same stylus over and over again. By applying the vertically undulating record to a disk tablet, and by giving the groove the proper configuration, I am enabled to accomplish the combined results of 35 both feeding the sound-box across the disk and of using the same needle for all reproductions. In the third place, if the ordinary reproducing stylus employed in cylinder machines be used with a vertically undulating groove deep enough to feed it, the stylus 40 will not enter the more minute irregularities, and the reproduction will be correspondingly defective.

Another object of my invention, then, is 45 to provide, in connection with a record-groove capable of feeding the sound box, a stylus that will give faithful reproductions from such record-groove.

The invention will be best understood by 50 referring to the accompanying drawings which illustrate the same.

Figure 1 is a cross-section, greatly enlarged, representing a recording-tablet and 55 the recording-stylus used in the present in-

vention; Fig. 2 is a similar view of the record-tablet employed in the present invention, showing my reproducer in connection therewith; and Fig. 3 is a plan view of a disk tablet, partly broken away, showing the position of the reproducing-stylus in connection therewith.

In making the record an angular or V-shaped recorder A is employed, which is connected with the diaphragm of a suitable sound-box in such a manner as to vibrate vertically in operative relation to a record-tablet B which is caused to rotate beneath the stylus A in the well known manner so as to receive a spiral groove. At a, a' 60 are represented the two sharp edges of the recorder A. These are shown as straight edges that converge at a right angle, each lying at an angle of 45° to the surface of the tablet B; but this angle may be more acute, or more obtuse, and instead of converging to a point, there may be more or less curvature or roundness. Obviously, the stronger 65 the impulse imparted to the diaphragm that actuates stylus A, the deeper will be the cut made into the record by the recorder, but the cross section of the cut at any place will always be the same as the profile of the recorder A. At b, b', b'', are illustrated cuts 70 or grooves of different depths.

The disk record B', in Fig. 3, may be obtained from the original record B (Fig. 1) by the well-known "Jones process" set forth in Patent No. 688,739, granted Dec. 10, 1901, to Joseph W. Jones *et al.* My new 80 reproducing-stylus C is shown as presented at an angle of 45° to the surface of tablet B', being secured in any convenient manner to the diaphragm-post d projecting from the center of the diaphragm D of the sound-box. This sound-box is arranged with its diaphragm substantially horizontal, and is carried on a swinging arm the same as in any of the well-known constructions employed in disk talking-machines. This 85 stylus C is preferably a small cylinder of sapphire, whose lower end is cut off square, practically the same article that is used as the recording-stylus for cylindrical records.

If the cross-section of the sound-groove shows two straight sides converging at a right angle, then the flat base of the cylinder C will rest against one side, and one "element" of the cylinder will rest against the other side of the cut; and, no matter 100

how deep or how shallow any portion of the cut may be, since the sides of the cut are always at (substantially) the same angle, the stylus will always enter the cut to the 5 full depth of the latter, consequently, a faithful reproduction will always be obtained. Furthermore, since these cuts are not the shallow, rounded affairs heretofore constituting record-grooves of this type, the 10 stylus C will be fed without any danger of "skipping."

If the cross-section of the record-grooves does not show an exact right angle, the 15 lower end of the stylus C may be more or less varied accordingly, as may be obvious, but the same benefits will be obtained in a greater or less degree.

Fig. 3 shows the stylus C as lying in the vertical plane through a radius of the disk 20 B', while Fig. 2 shows that the stylus is at an angle of 45° to the surface of the disk; but instead of lying in a radial plane, the stylus may be in some other plane as indicated by the dotted lines C', and it may also 25 be at an angle somewhat greater or less than exactly 45°. But in any variation, the stylus will still be "diagonal" to the record-groove.

Having thus described my invention 30 fully, I claim:

1. The combination of a tablet having a spiral sound-groove the walls of which groove converge at an angle, and a stylus

presented transversely of said groove and at less than a right angle to said tablet, the 35 end of the stylus engaging one wall of the groove and the side of the stylus engaging the other wall of the groove.

2. The combination of a disk tablet having a spiral sound-groove characterized by 40 vertical irregularities, a diaphragm, and a stylus entirely supported by said diaphragm and lying in the vertical plane through a radius of said disk, said stylus being presented at an angle of approximately 45° to 45 the surface of the disk.

3. In a talking machine, the combination of a tablet containing a vertically undulating sound-groove whose walls converge at an angle of approximately 90°, and a reproducing stylus whose end face engages one 50 wall of the groove and whose side engages the other wall of the groove.

4. The combination of a disk tablet having a spiral sound-groove characterized by 55 vertical irregularities, a diaphragm, and a stylus entirely supported by said diaphragm and lying in the vertical plane through a radius of said disk.

In testimony whereof I have signed this 60 specification in the presence of two subscribing witnesses.

VICTOR H. EMERSON.
